UNITED STATES PATENT OFFICE.

JOHN C. NACE, OF JOHNNETTA, PENNSYLVANIA.

HEATING APPARATUS.

SPECIFICATION forming part of Letters Patent No. 749,086, dated January 5, 1904.

Application filed July 2, 1903. Serial No. 164,026. (No model.)

To all whom it may concern:

Be it known that I, JOHN C. NACE, a citizen of the United States, residing at Johnetta, in the county of Armstrong and State of Pennsylvania, have invented a new and useful Improvement in Heating Apparatus, of which improvement the following is a specification.

This invention relates to a certain new and useful improvement in heating apparatus, and relates more particularly to what is known as "hot-air furnaces."

The object of this invention is to provide a heating-furnace whereby the entire heat generated by the furnace is utilized.

15 A further object of this invention is to provide means whereby the loss by radiation is reduced to a minimum.

With the above and other objects in view my invention consists in the novel design, 20 combination, and arrangements of parts, as will be more fully hereinafter described, and specifically pointed out in the claim.

In describing the invention in detail reference will be had to the accompanying drawings, forming a part of this specification, in which like reference - numerals designate like parts throughout the several views, in which—

Figure 1 is a sectional side elevation of my 30 improved heating apparatus, a portion thereof being broken out. Fig. 2 is a front elevation of the same. Fig. 3 is a plan view of the cap-piece. Fig. 4 is a sectional plan through the vertical flue of the apparatus. Fig. 5 is 35 a sectional plan of the combustion-chamber. Fig. 6 is a plan view of the brick flue-support located around the combustion-chamber.

In describing the invention the reference-numeral 1 indicates the combustion-chamber, 40 in which the usual grate 2 is provided and the fire-doors 3 and ash-doors 4 are placed upon the furnace, substantially as shown. The upper portion of this chamber 1 is contracted, as shown at 5, and a plurality of sectional flues 6 are connected with said chamber and placed one above the other. Lugs 7 are placed in the lower inside corners of each section, whereby the said sections are held in alignment, and ribs 8, placed on the outside 45 of said sections, form a means whereby the

wall of bricks may be held a proper distance away from said sections, thereby forming an air-space 9 between said sections and the wall 10, formed therearound.

The wall 10 at its lower end is tapered to 55 conform to the shape of the combustion-chamber, and the said tapered portion rests on the support 11, which in turn is supported by the offsets formed in the ribs 8 of the combustion-chamber.

60 The lower end of the air-chamber 9 is connected with any suitable air-supply, which is indicated by the reference-numeral 12. The wall 10 has apertures 14 formed therein at the points of outlet for the heated air, and 65 any suitable form of "register" or control may be placed therein.

In order that the products of combustion may not rush through the flue without heating the air confined therearound, the top of said 70 flue is partially closed by the plate 15, the said plate also extending over and closing the air-chamber 9.

75 While I have herein described my invention in detail, it will be obvious that the unit system of construction will permit any extension of the structure and that various slight changes may be made in the details of construction without departing from the general spirit of my invention.

80 Having fully described my invention, what I claim as new, and desire to secure by Letters Patent, is—

In a heating-furnace the combination of a combustion-chamber having a contracted upper portion, a plurality of ribs formed on the outer side of said chamber, a plurality of flue-sections placed one above the other and connecting with the contracted portion of the combustion - chamber, a plurality of lugs 85 formed on the end of the flue-sections whereby the different sections are connected a plurality of ribs formed on said flue-sections, a wall formed around the ribs of the flue-sections and combustion-chamber, a plate placed 90 over the upper flue-section for closing the upper end of the chamber formed between the flue-sections and the wall built therearound, an aperture formed in said plate, said aperture being of lesser area than the 95 100

interior of the flue-sections thereby decreasing the outlet from said flue, apertures formed in said wall for withdrawing the air contained between said wall and flue-sections and connections with the lower end of this space whereby fresh air may be admitted to the same, substantially as described.

In testimony whereof I have hereunto signed my name in the presence of two subscribing witnesses.

JOHN C. NACE.

In presence of—
GEO. E. NACE,
REBECCA HOWE.
